ELECTROLYTIC CONDENSER

Samuel Ruben, New Rochelle, N. Y.

Application October 26, 1937, Serial No. 171,004

10 Claims. (Cl. 175—315)

This invention relates to electrolytic condensers. A general object is the provision of electrolytic condensers of both "dry" and "wet" type which are of new, novel and simple design, which 5 can be produced at a low cost, which provide maximum capacitance for a given volume and which to a large extent may be manufactured by machine with a minimum of labor.

An object of the invention is the provision of 10 an electrolytic condenser in which the anode, cathode and spacer are combined in a unitary structure.

A further object is the provision of an electrolytic condenser in which both electrodes and the 15 spacer are united in a single woven cloth.

Another object is the provision of a unitary electrolytic cell structure composed of a woven cloth, the shoot of which is insulated from the warp.

20 Still another object is to provide a unitary cathode-anode spacer structure by weaving together two metal strands insulated from each other by a porous spacer wound around at least one of said strands.

25 Another object is the provision of an electrolytic device having two or more capacitances in a single unit.

A further object is to provide a multi-capacitance condenser in the form of woven cloth having 30 a plurality of separated warps serving as anodes in relation to and electrically insulated from the shoot strands, serving as a common cathode.

Further objects will be apparent from the disclosure and from the drawing, in which,

35 Fig. 1 is a face view of a unitary cathode-anode spacer construction made according to this invention;

Fig. 2 is a view showing in detail the arrangement of cathode, anode and spacer;

Fig. 3 is a face view of a structure which comprises two capacitances in a single unit;

Fig. 4 is a view of the structure shown in Fig. 1 in semi-rolled form, and

Fig. 5 shows a condenser mounted within a container.

Dry electrolytic condensers as heretofore commercially manufactured comprise two cooperating electrodes of film forming metal such as 50 aluminum or tantalum, at least one of the electrodes having electrolytically formed on its surface an immeasurably thin film of oxide which serves as the dielectric. The electrodes are separated by absorbent spacers such as gauze, paper, 55 non-fibrous sheet cellulose or combinations of

these spacers, and the electrolyte employed is a viscous film maintaining composition which may be a heavy paste, or only slightly viscous. As the condensers are usually constructed in roll form, at least two spacers are required in order to prevent short-circuiting of the electrodes. Thus, the manufacture of the condenser requires the handling of two rolls of foil and two or more rolls of spacer, such as "Cellophane", paper, gauze, et cetera. If the condensers are "wet" wound, that is, if the foils and spacers are drawn through the viscous electrolyte in the winding process, difficulty is sometimes encountered in lining up the rolls and in preventing "telescoping". If the condensers are "dry" wound and thereafter impregnated with the electrolyte, the tight winding of the foils and spacers retards the absorption of the viscous electrolyte by the spacer and makes necessary a long immersion period and in some cases, a centrifuging operation.

In my co-pending application bearing Serial Number 162,401, filed September 4, 1937, of which this application is a continuation in part, I describe the use of woven metal cloth as an electrode in order to obtain a high capacitance in a small area. I also describe in that case, a structure comprising a cloth woven from cotton-covered aluminum wire, the cotton winding allowing an increased effective area and capacity and eliminating the use of separate spacer elements.

In the present invention I utilize cloth having a weave somewhat similar to that shown in my aforesaid co-pending application, but go a step further and provide cathode, anode and spacer in a single woven structure. In this new condenser the shoot may be composed of electrolytically oxidized aluminum wire which serves as the anode and the warp may be composed of double cotton-covered aluminum wire, or the warp may be the anode and the shoot the cathode. The two strands are woven into a close mesh cloth, preferably in ribbon form, about two inches wide with a selvage edge. The anode threads should be very closely spaced in order to afford the maximum effective area.

The warp may to advantage be composed of large diameter wire when the unit is used on direct current. For example, I have used as warp strands .010 inch diameter cotton-covered aluminum wire, which strands serve as the cathode, and for the anode or shoot wire I have used .005 inch diameter aluminum with a 200 x 24 twill weave. In some cases a plain weave is desirable, while in other cases a twill weave is of advantage.

If the condenser is to be used on alternating

current, the warp and the shoot are both electrolytically oxidized or formed and are of equal area so as to avoid assymetrical conductive effects.

The manufacture of the condenser section is exceedingly simple, the woven ribbon being merely wound into roll form and immersed in the electrolyte.

While aluminum wire is considered the most suitable film-forming material, other metals, such as tantalum, magnesium or alloys of these metals with aluminum, may be utilized. I prefer to form or oxidize the wire prior to the time it is woven into the cloth, but the forming may, of course, take place after the weaving. To increase the capacitance of the unit the wire prior to forming, may be etched in a manner well known to the art, for instance, by immersing in a bath of copper-chloride or in a mixture of hydrofluoric and hydrochloric acids.

20 Cotton is the preferred material for use as a spacer element and as an electrolyte-absorbing material but other spacers capable of being wound or wrapped upon the wire may be used, for example, "Cellophane", paper, rayon or a 25 combination of paper and "Cellophane", cemented together with a conductive cement. The cotton-covered wire may, if desirable, be sized with methyl cellulose plasticized with a glycol, thus providing a film between the cotton fibres, 30 having properties somewhat akin to "Cellophane".

While in most cases it will be desirable to cotton-cover only one of the electrodes, namely, the warp, both the warp and shoot may be advantageously covered for some purposes. Where both electrodes are covered, the maximum quantity of electrolyte is held in contact with the electrodes. Where both warp and shoot wires are cotton-covered, plain thin aluminum foil can 40 with advantage be used in contact with each side of the cloth in order to reduce the current path length and thus maintain a low power factor. Such a sheet of foil can also be used to advantage on direct current condensers where the 45 anode is a cotton-covered shoot and the cathode is the plain aluminum wire warp. In the latter structure the foil would be connected to the warp.

Where it is desired to provide different values of capacitance in the same unitary condenser structure, the warp or the shoot may be utilized as a common cathode. If the warp is the common cathode, the selvaged edge with the shoot or bare wire is cut and several strands of the shoot wire pulled out, thus electrically separating the shoot weave. Contact is made with the shoot wires brought out from the various separated sections, thus allowing a simple and economical method of obtaining multi-capacitance units.

60 The structure may also be used for polarized cells of the iron or nickel type, employing alkaline electrolytes which operate below the decomposition potentials of the electrolyte.

In order to more fully describe certain forms 65 of the invention, reference is made to the attached drawing. In Fig. 1, the unitary structure 1, comprising the anode, cathode and spacer, has been partly cut away at one end section to provide anode tab 2, and at the opposite section 70 the cotton covering has been stripped from cathode wire 3, which is clamped in cathode terminal 4.

In Fig. 2, the anode wire 6, is shown woven in continuous form between the strands of cotton 75 covering 5, of wire 3.

In Fig. 3, sections 1_a and 1_b are separate electrical capacitances having terminals 2_a and 2_b respectively, the selvaged edge of the structure, similar to that shown in Fig. 1, having been cut away at 7 and 8, and strands of the shoot having been withdrawn from the area 9. In the manufacture of the cloth, the machine can be adjusted so as to automatically provide the desired spacing, thus eliminating the necessity of cutting the selvage or removing some of the 10 threads. Cathode warp wires 3 are clamped into cathode terminal post 4, which serves as the common cathode for anodes 1_a and 1_b.

While the invention is especially useful in connection with dry or plastic-type electrolytes of 15 the type described in my United States Letters Patent 1,710,073; 1,714,191; 1,891,207; 1,918,716; 1,918,717, et al., the structures shown or modifications thereof may be advantageously used in wet electrolytic condensers, especially where it is 20 desired to provide two or more capacitances in a single unit. For instance, the structure shown in Fig. 3 may be modified to substitute enameled copper wire for the cotton-covered aluminum cathode 3, the enameled insulation being removed 25 at the terminal of the wire to provide contact with terminal member 4 and the electrolyte.

Fig. 4 shows the condenser structure of Fig. 1 in semi-rolled form.

In Fig. 5 a condenser section 10, comprising 30 the structure illustrated in Fig. 1 in roll form has been impregnated and wrapped with varnished paper 11, and mounted in container 12, from which it is insulated by pitch 13. The container is sealed by Bakelite top 16, through 35 which are brought out terminals 14 and 15.

The structure of the condenser lends itself readily to a simple impregnation process. Due to the unitary structure, no difficulty is experienced in thoroughly impregnating every part of 40 the condenser, and due to the close association of the spacer element with the film-forming electrodes a maximum quantity of electrolyte is always in contact with both cathode and anode. This is, of course, particularly true when a viscous 45 fluid electrolyte of the glycol-ammonium borate type is used. As not only is this type of electrolyte thoroughly absorbed in the cotton spacer, but due to its viscous character and the woven surface of the cathode-anode structure, 50 it tends to adhere to all parts of the condenser unit.

Having described my invention, what I claim as new and desire to secure by Letters Patent, is:

1. An electrolytic condenser comprising an 55 aluminum cloth, the shoot constituting one electrode and the warp the other electrode, a spacer around at least one of said electrodes so as to insulate it from the other electrode, and an electrolyte.

2. An electrolytic condenser comprising a metal cloth, said cloth comprising metal wires at least one of which is a film forming metal, the shoot constituting one electrode and the warp the other 65 electrode, a spacer around at least one of said electrodes so as to insulate it from the other electrode, and an electrolyte in said spacer and in contact with both electrodes.

3. An electrolytic condenser comprising a metal cloth, the shoot constituting one electrode and the warp constituting the other electrode, an electrolyte permeable cellulose spacer around at least one of said electrodes so as to insulate it from metallic contact with the other electrode, 75

and an electrolyte in said spacer in contact with both electrodes.

4. An electrolytic condenser comprising a metal cloth, the shoot constituting one electrode and the warp constituting the other electrode, an electrolyte permeable cellulose spacer around at least one of said electrodes so as to insulate it from metallic contact with the other electrode, and a viscous film forming electrolyte in said spacer and in contact with both electrodes.

5. An electrolytic condenser comprising a metal wire cloth, at least one of said wires being a film forming metal, the shoot constituting one electrode and the warp the other electrode, the film forming metal wire being chemically etched so as to increase its capacity and having a dielectric oxide film formed on said etched surface, a spacer around at least one of said electrodes so as to insulate it from metallic contact with the other, and an electrolyte in said spacer and in contact with both electrodes.

6. An electrolytic condenser comprising an aluminum cloth, the shoot constituting one electrode and the warp the other electrode, at least one of said electrodes comprising film forming metal, an electrolyte permeable cellulose spacer spirally wound around at least one of said electrodes so as to insulate it from metallic contact with the other, and an electrolyte in said spacer and in contact with both electrodes.

7. An electrolytic condenser comprising a metal cloth, the shoot constituting one electrode and the warp the other electrode, at least one of said electrodes comprising a film forming metal

etched to increase the effective surface area thereof, a dielectric oxide film formed on said etched electrodes, an electrolyte permeable cellulose spacer wound spirally around at least one of said electrodes so as to insulate it from the other electrode, and a viscous film forming electrolyte impregnating said condenser structure.

8. An electrolytic condenser comprising a woven metal cloth immersed in an electrolyte, one set of parallel strands of said cloth comprising the cathode, and a plurality of sets of parallel strands transverse to said first set comprising anodes, an insulating spacer directly spirally wound around at least one set of parallel strands so as to insulate it from metallic contact with the said transverse strands, an electrolyte in said spacer and in contact with said cathode and anodes.

9. An electrolytic condenser comprising a woven metal cloth immersed in an electrolyte, one set of parallel strands of said cloth comprising the cathode, and a plurality of sets of parallel strands transverse to said first set comprising anodes, a coating on said cathode strands to insulate said cathode from the anodes, and an uninsulated portion of said cathode not in contact with said anodes but in direct contact with said electrolyte.

10. A dry electrolytic condenser comprising a container having therewithin an aluminum cloth, the shoot constituting one electrode and the warp another electrode, a spacer around at least one of said electrodes so as to insulate it from said other electrode, and a viscous electrolyte.

SAMUEL RUBEN.
